UNITED STATES PATENT OFFICE.

WILLIAM D. WATKINS, OF SAN JOSE, CALIFORNIA, ASSIGNOR TO WATKINS
MANUFACTURING COMPANY, OF SAN JOSE, CALIFORNIA.

TELEPHONE SYSTEM.

SPECIFICATION forming part of Letters Patent No. 784,088, dated March 7, 1905.

Application filed March 11, 1902. Serial No. 97,729.

To all whom it may concern:

Be it known that I, WILLIAM D. WATKINS, a citizen of the United States, residing at San Jose, in the county of Santa Clara and State of California, have invented a new and useful 5 Telephone System, of which the following is a specification.

This invention relates to certain improvements in selecting devices for telephone systems, and has for its principal object to provide means for cutting out every subscriber from the talking-circuit and permitting the central station to connect any two subscribers on party-lines without connecting any other 15 subscriber on the system.

A further object of the invention is to provide means for automatically closing the talking-circuit of any selected subscriber by energizing the calling-circuit of such subscriber, 20 all of the subscribers being normally connected to central through the calling-circuit and all of the local talking-circuits being normally open.

A still further object of the invention is to 25 provide means whereby a subscriber calling central may retain sole control of the calling-circuit until answered by central, the mechanism being such that no other subscriber is allowed to call central until the central station 30 has answered the first call.

A still further object of the invention is to 35 provide for the return of the switch of the talking-circuit to initial position to cut out the local talking-circuit after a subscriber has finished using the telephone.

A still further object of the invention is to 40 provide for the signaling of a selected number to central by the operation of the receiver-hook.

With these and other objects in view the 45 invention consists in the novel construction and arrangement of the parts and the system hereinafter described, illustrated in the accompanying drawings, and particularly pointed out in the appended claims.

In the drawings, Figure 1 is a perspective view of the switch-box of a telephone provided with selecting mechanism and automatic switching devices arranged in accord-

ance with my invention. Fig. 2 is a detail of 50 the clapper-actuated mechanism for releasing the automatic switch. Fig. 3 is a similar view of the switch and a portion of the mechanism for returning the same to an initial position. Fig. 4 is a detail sectional view of the mechanism for automatically returning the switch to initial position by the return of the receiver to its supporting-hook. Fig. 5 is a diagram illustrating the wiring of a telephone in accordance with the invention and illustrating also a portion of the calling-circuit at central station. Fig. 6 is a view similar to Fig. 5 illustrating a modified system of wiring for use in connection with a receiver-hook calling system. Fig. 7 is a diagram illustrating 55 a central station and two local stations connected therewith. Fig. 8 is a detail view of the central-station indicator.

In the drawings is illustrated a telephone switch-box 10, which may be employed in 70 connection with any suitable form of telephone or microphone. The receiving and transmitting devices form no part of the present invention, and therefore have been omitted from the drawings, except so far as the circuits are shown in Figs. 5 and 6.

The present invention is designed for use in connection with party-lines when each subscriber on the line is designated by a different numeral, each telephone being provided with 80 selecting mechanism adjusted to respond only to the closing of the calling-circuit a number of times equal to the number by which the telephone is known, and central is also provided with mechanism which while responding to the 85 call of each subscriber on the line will immediately indicate the number of the subscriber calling.

The main-line wires 11 and 12 extend from the central station to the various subscribers 90 along the line, and in the main line at the central station are a pair of electromagnets 13, as indicated in Figs. 5, 6, and 8, which when energized by the closing of the calling-circuit by any subscriber along the line attract an armature 14, pivoted at one end on a suitable stud 15 and carrying at the opposite end a pawl 16, adapted to operate on a ratchet-wheel 17,

successive closings of the circuit effecting a step-by-step movement of said ratchet-wheel. The ratchet-wheel is held from movement in reverse direction by a retaining-pawl 18, and 5 on its supporting-spindle 19 is mounted a hand or pointer 20, adapted to travel over an indicating-dial 21, the latter being spaced and provided with numerals equal to the number of subscribers on the party-line in which the 10 electromagnets are situated. A subscriber wishing to call central successively closes the calling-circuit at his telephone a number of times equal to the number of his telephone, causing corresponding movements of the armature and a step-by-step movement of the ratchet-wheel, which results in the travel 15 of the hand or pointer over the indicating-dial until the number of said subscriber is reached, thus indicating to central the number 20 of the subscriber who desires to open communication. Each subscriber, as will hereinafter more fully appear, is provided with means for closing the circuit the desired number of times, the circuit being held closed 25 at the last movement and keeping the electromagnet energized and the armature attracted until central responds by energizing the circuit in which said subscriber's call-bell is situated. The hand or pointer 20 is so mounted 30 on the shaft or spindle 19 as to permit its being moved back to an initial position by the operator at central without disturbing the position of the ratchet-wheel; but the frictional contact of the pointer and spindle is sufficient to cause the movement of the pointer 35 as the spindle and ratchet-wheel are rotated. To return the hand or pointer to initial position, the operator must close the subscriber's calling-circuit, the movement of the pointer 40 to its initial position automatically effecting the closing of such circuit.

The arrangement of the circuits is such that when a subscriber holds the circuit closed at the end of the call to central, the electromagnet 45 13 will be energized and will hold the armature down so that it cannot be affected by the closing of the circuit by another subscriber also wishing to call central, the first subscriber having sole control of the line and 50 the pointer being held in adjusted position until the subscriber opens the circuit and permits the armature to withdraw from the magnets, when the magnet may be controlled in the same manner by any other subscriber 55 wishing to call central. This arrangement prevents confusion of signals at the central station and compels the operator at central to answer the calls in the order in which they are received, it being impossible for more than 60 one subscriber to call up central at the same time.

Each telephone on the system is provided with means for closing the calling-circuit, and in the drawings I have illustrated two methods 65 of accomplishing this result, the wiring in

one case being so arranged that the subscriber may close the circuit the desired number of times to represent the number of his telephone by lowering and raising the receiver-hook. In the other case an auxiliary switch is arranged in the circuit, the switch being adapted to travel over a number of contacts representing the number of the telephone. When an auxiliary switch is employed, it preferably takes the form of a switch-arm 22, pivoted on a stud 23 on the lid of the switch-box 10 or at other convenient points on or near the other portions of the apparatus. The stud 23 is located centrally of a number of contact posts or blocks, four of which are shown in the 80 present instance, the number of the subscriber being "3" and the additional block being that on which the end of the switch-arm normally rests when the talking-circuit is being used and between intervals of use of the telephone. 85 The three blocks 24, 25, and 26 are electrically connected to each other and to a wire 11, leading from the main-line wire 11, the connection being made through one of the hinges between the switch-box and its lid, while the 90 additional block 27 is connected by conductors 28 and 65 to the receiver-hook switch 29, for a purpose hereinafter set forth. On the inner surface of the box-lid, at a point below the block 27, is a metallic plate 30, having 95 perforated ears for the support of a short spindle 31, carrying two arms 32 and 33, disposed approximately at a right angle to each other, the arm 32 making contact with one or the other of contact-fingers 34 and 35. The 100 arm 33 at its upper or outer end is bent at a right angle or in a plane parallel with the spindle 31 and is provided with two laterally-projecting fingers 36, having enlarged heads and forming spring-catches for engagement 105 with the lower end of arms or levers 37 38, which are pivoted intermediate of their length on studs 39 and so disposed at their lower ends as to move toward each other by gravity. The upper ends are arranged one on each 110 side of the clapper 40 of the electromagnetic call-bell 41 and in the path of movement of such clapper, so that when the electromagnets of the call-bell are energized and the clapper is vibrated the arms will be moved and will 115 free the catches 36, permitting the arm 33 to fall by gravity from a vertical to a horizontal position. The lower ends of the levers 37 38 are disposed in a suitable guide-box 42 to prevent any outward movement from the weight 120 of the switch, and to prevent inward movement when the switch-lever is returned to vertical position and the catches 36 are engaged with the levers 37 38. Only one of the levers and catches is in engagement at one time, the 125 clapper-rod 40 stopping either at one side or the other and in engagement with one of such arms or levers and holding the same out of contact with its catch 36, but in all cases holding the other in position to be engaged by its 130

catch 36. In Fig. 2 the lever 37 is in a disengaged position, while the lever 38 is in position to engage with one of the catches 36 and is directly in the path of movement of the 5 clapper-rod, the first movement of the latter shifting the arm and effecting its disengagement from the holding-catch.

When the arm 33 is in the horizontal position, as indicated in Figs. 1 and 3, it rests 10 on one end of a lever 44, pivoted on a pin 45, the opposite end of said lever being operated upon by a spring 46, which normally holds the upper edge of the lever against a stop-pin 47, the latter limiting its movement and serving, through the lever 44, to prevent excessive downward movement of the switch-lever. The inner end of lever 44 engages with the under side of the arm 33 at a point close to the fulcrum of the latter, so that a slight upward movement to the extent indicated by 15 dotted lines in Fig. 3 will be sufficient to move said arm from the horizontal to the vertical position and cause the engagement of one of the holding-catches 36 with one or other of the levers 37 38.

In order to effect the automatic return of the arm 33 to the vertical position after a subscriber has finished talking, I provide on the receiver-hook 50 a spring 51, having a rounded 20 boss 52 in which is formed a notch 53, and on the inner face of lever 44 is arranged a flange or lug 54, adapted to enter into said notch when the receiver-hook is in the elevated position. At a point some distance below the 25 outer end of lever 44 is a projecting tongue 55 with which the rounded boss 52 is adapted to engage as it reaches the limit of downward movement during the descent of the receiver-hook, the spring 51 being thus pushed inward and the boss 52 moved a distance sufficient to 30 disengage the lug 54 from the notch 53, after which the lever 44 is returned to its initial horizontal position in readiness to receive and support the arm 33 at the next operation.

In addition to the automatic mechanism for 35 returning the arm to initial position I may employ an auxiliary crank-pin or cam 56 on the inner end of the stud 23 of arm 22, said crank-pin being so disposed with relation to the arm 40 that the latter being in normal position in contact with the block 27 the first movement of the arm in the direction of contact-block 24 will cause the engagement of the crank-pin with the under side of the lever 44 and 45 will elevate the arm to the vertical position.

The electromagnets of the call-bell 41 of each telephone are in circuit with the main-line wire 11 through a conductor 60, which extends to ground, so that the central station 50 may at any time ring the bell by energizing the line 11.

A subscriber wishing to call central turns his switch-arm 22 from contact with the block 27 to contact with the first of the signaling-blocks 24. The circuit is then completed from

main line 11, conductor 11', block 24, switch-arm 22, stud 23, to a conductor 61, which connects the stud to the plate 30. The current flows through plate 30, spindle 31, arm 32, contact-spring 34, and wire 12' to the main-line wire 12, energizing the central-station magnet 13 and moving the ratchet to the extent of one tooth. The further movement of switch-arm 22 from contact with the block 24 opens the circuit and releases the armature, 70 the pointer, however, remaining opposite the numeral "1" on the dial. The further movement of switch-arm 22 to contact with block 25 produces a similar result to that effected by its contact with the block 24, and in similar 75 manner the circuit is closed for the third time when the switch-arm makes contact with the block 26, where it is allowed to remain, keeping the magnet 13 at the central station energized and holding the hand or pointer over 80 the indicating-dial opposite the numeral "3" and preventing any other subscriber from moving the indicator by opening the circuit of the magnet. Central then answers the call and energizes the magnets of the call-bell 41, 85 90 the first movement of the clapper-rod effecting a movement of one or other of the levers 37 38, releasing the switch-arm 33, which falls to horizontal position and moves the arm 32 from contact with the contact-spring 34 to the 95 lower contact-spring 35. As the subscriber raises the receiver from the hook the inner end of the latter is moved into contact with the two receiver-hook contacts 29 29', placing such contacts in electrical communication and 100 establishing a circuit through both the receiver and the transmitter. The circuit may be traced through main-line wire 12 and receiver to receiver-hook contact 29', receiver-hook contact 29, wire 65, wire 28, contact-block 27, switch-arm 22, (which has been moved to normal position after central has answered the call,) stud 23, wire 61, plate 30, spindle 31, arm 32, spring 35, wire 66, wire 67, the transmitter, and wire 68 to main-line 105 110 wire 11.

After the subscriber has finished talking he places the receiver on the hook, causing the descent of the hook and the movement of the lever 44 through its engagement with the 115 notched boss 52 and raising switch-arm 33 to the initial position in readiness for another call. As this return of the arm to its initial position is accomplished automatically, the subscriber immediately cuts himself out of the 120 talking-circuit and cannot by again removing the receiver from the hook listen to any conversation on the line, nor can he communicate with any person, except through the signaling-circuit, until central by energizing his 125 call-bell 41 releases the arm 33 and closes the local talking-circuit.

The device as thus far described necessitates the employment of the auxiliary switch-arm 22 and the several contact-blocks on the call- 130

ing-circuit; but the switch-arm and contact-blocks may be dispensed with and the wiring simplified to a considerable extent by arranging the system as indicated in Fig. 6.

- 5 In Fig. 6 the system is practically the same as that heretofore described and illustrated in Fig. 5, the various contact-blocks 24 25 26 27 and the switch-arm 22 being dispensed with. The corresponding portions of Figs. 5 and 6 10 are designated by the same reference-numerals, and it will be observed that, as before, the call-bell 41 is in a circuit extending from main-line wire 11 to wire 60 to ground. The only break in the circuit, except that made 15 by the previously-described movement of the switch-arm 33, is at the receiver-hook contacts 29 and 29'. When a subscriber wishes to signal his telephone-number to central, he raises the receiver-hook a sufficient number 20 of times, each upward movement of the hook closing the circuit between contacts 29 29' and establishing a circuit which may be traced through main-line wire 11, wire 11', spring 34, arm 32, spindle 31, plate 30, wire 65, contact 29, receiver-hook, contact 29', wire 70, the receiver, main-line wire 12. After receiving 25 an answer from central the switch-arm 33 is dropped, and the receiver being removed from the hook the talking-circuit may be traced 30 from main-line wire 12 through the receiver, wire 70, contact 29', the receiver-hook, contact 29, wire 65, plate 30, spindle 31, arm 32, spring 35, wire 67, the transmitter, and wire 68 to main-line wire 11.
- 35 The mechanism at the central station may be of the most simple character and includes, in addition to the indicator, a battery X and call-bell Y, arranged in the main-line. In addition to this central is provided with a 40 ground-wire 80, connected to the main line, and in this wire is a source of electrical energy, as indicated at 81, for sending an alternating current over the line, and a switch 82, by which the current may be controlled, the 45 operator closing the switch for a number of times, dependent on the number of the subscriber to be called, in order to operate the selecting mechanism and then holding the circuit closed for a sufficient length of time to 50 cause the ringing of the call-bell of the selected subscriber. At central station is also shown an operator's talking set, including the usual transmitter, receiver, and local battery, the secondary being bridged across the 55 main line.

The system is wholly and completely under the control of central, and no other subscriber except those whose call-bells and switch-arms 33 have been operated by central can use the 60 talking-circuit or listen to any conversation on the line.

In order that central in sending a calling-signal may operate only the bell of the desired subscriber, I employ in connection with

the bell and its operating-magnet a selecting 65 mechanism, which may be of the character shown in Letters Patent No. 695,976, granted to me on June 26, 1902, or of any other character suitable for the purpose, the selecting mechanism being so arranged as to engage 70 the clapper of the bell and normally lock the same until the operator at central releases it by closing the circuit the proper number of times.

While the construction herein described and 75 illustrated in the accompanying drawings is the preferred form of the device, it is obvious that various changes in the form, proportion, size, and minor details of the structure may be made without departing from the spirit or 80 sacrificing any of the advantages of the invention.

Having thus described my invention, what I claim is—

1. A telephone system including a signaling 85 and a talking circuit, an electromagnetically-actuated selecting device arranged in the signaling-circuit, a call-bell controlled by the selecting device and including a movable member, and a switch controlled by said movable 90 member for placing the local talking-circuit in communication with the main line.

2. In a telephone system, a main line, a central station, a plurality of telephones connected therewith, the local talking-circuit of each 95 telephone being normally cut out independently of the receiver-hook contacts, a switch normally locked in open position and disposed in said local talking-circuit, a selecting device 100 controlling the switch, and a local signaling-circuit for operating the selector, said signaling-circuit being in constant communication with the main line, and means operable from the central station for operating the selector and releasing the switch to permit the closing 105 of the local talking-circuit.

3. In telephony, a main line, a local signaling-circuit, a selecting mechanism, a call-bell controlled by the selecting mechanism, a normally cut-out talking-circuit, and a switch 110 disposed in said talking-circuit and normally held in open position, said switch being released and closed by the vibratory movement of the bell-clapper.

4. A telephone system comprising a main 115 line, a local signaling-circuit in constant communication with the main line, a selecting mechanism and an electromagnetically-operated bell in the signaling-circuit, a normally cut-out local talking-circuit, and a switch in 120 said talking-circuit, said switch being operably connected to the clapper of the bell and being released from a normally locked position when the clapper is actuated to thereby connect the local talking-circuit to the main line.

5. In a telephone system, a main line, and a central station, a normally cut-out local talking-circuit, a signaling-circuit in constant

communication with the main line and including a call-bell, a selecting mechanism arranged in said signaling-circuit and controlling the operation of the call-bell, said selecting mechanism being under the control of the central station, and a switch operable on the sounding of the call-bell and serving to place the local talking-circuit in communication with the main line.

10 6. In a telephone system, the combination with the main line, a local talking-circuit disconnected from the main line independently of the receiver-hook-controlled contacts, a signaling-circuit constantly connected in the main line, a switch under the control of the signaling-circuit for placing said talking-circuit in communication with the main line, and manually operable means at each station for returning said switch to an initial position 20 after each operation.

7. In a telephone system, a main line and a plurality of telephones, the local talking-circuit of each telephone being normally disconnected from the main line, a local signaling-circuit in constant communication with the main line and including a call-bell, a switch for placing the local talking-circuit in communication with the main line and a selecting mechanism in the signaling-circuit controlling the operation of the call-bell, the movement of the bell-clapper effecting the closing of the switch and placing the talking-circuit in communication with the main line.

8. In a telephone system, the combination with a party-line and a series of telephones each having its local talking-circuit out of communication with the main line, of a grounded local signaling-circuit including a bell constantly connected in the main line, a switch for placing the local talking-circuit in communication with the main line and controlled by the movement of the bell-clapper, an electro-mechanically-operated selecting mechanism located in the signaling-circuit and controlling the movement of the bell-clapper.

9. A party-line telephone system comprising a main line, a telephone having its local talking-circuit normally cut out from the main line, a signaling-circuit, a switch having a pivotal support and adapted to place the local talking-circuit in communication with the main line, an electromagnetic call-bell located in the signaling-circuit, a pair of pivoted arms disposed one on each side of the clapper-rod of said bell and serving to hold the switch in elevated position, and means for returning the switch to an initial position.

10. In a telephone system, a normally open local talking-circuit, a normally closed signaling-circuit, a call-bell arranged in the signaling-circuit, a pair of pivoted arms situated one on each side of the clapper-rod of the bell and adapted to be operated thereby, a pivoted switch arranged in the talking-circuit and having devices for engaging said pivoted arms, a

lever for raising the switch to open position, and means for operating said lever.

11. In a telephone system, a normally open local talking-circuit, a normally closed signaling-circuit, a call-bell arranged in the signaling-circuit, a pair of pivoted arms arranged one on each side of the clapper-rod and adapted to be operated thereby, a pivoted switch arranged in the talking-circuit and having devices for engaging said pivoted arms, a lever for returning the switch to open position, and a yielding boss carried by the receiver-hook of the telephone for engagement with said lever.

12. The combination of the switch, means for dropping said switch to closed position, a lever for returning the switch to open position, said lever having a projecting tongue or flange, a receiver-hook, a spring carried thereby, a notched boss mounted on the spring for engagement with said flange or tongue, and means for effecting the disengagement of the notched boss from the flange or tongue after the switch has been moved to open position.

13. The combination with a signaling-circuit, of a gravity-switch, means for dropping the switch to closed position, a lever for returning the switch to open position, a revoluble contact-switch arranged in the signaling-circuit, and a crank-arm carried by said revoluble contact-switch for engagement with the returning-lever, substantially as specified.

14. The combination of the local talking and signaling circuits, a pivotally-disposed switch, means for connecting the switch with one of the line-wires, contact-springs adapted for engagement by the switch and situated one in the signaling-circuit and the other in the talking-circuit, and mechanism under the control of the signaling-circuit for permitting a movement of the switch to engage the contact-spring in the talking-circuit and thereby close said circuit through the line-wire connected with the switch, substantially as specified.

15. The combination with a normally open local talking-circuit, of a signaling-circuit, a switch, means under the control of the signaling-circuit for permitting a movement of said switch to close the talking-circuit, a series of contact-blocks arranged in the signaling-circuit, and a revoluble switch in the signaling-circuit adapted to make contact with the successive blocks, said revoluble switch being provided with means for engaging the switch of the talking-circuit and returning the same to open position.

In testimony that I claim the foregoing as my own I have hereto affixed my signature in the presence of two witnesses.

WILLIAM D. WATKINS.
